Application November 26, 1945, Serial No. 630,812

27 Claims. (Cl. 250—145)

1

This invention relates to electron discharge devices and is concerned more particularly with a device of that type which comprises an anode and cathode of novel construction and arrangement, together with a new means for deflecting electrons issuing from the cathode and focusing them upon the face of the anode. The cathode includes an incandescent filament, which is of large size and capable of producing a large quantity of electrons, and the cathode encircles the anode and may be so mounted that the cathode and the supporting means therefor are wholly outside any hemisphere subtended by the plane of the face of the anode. The invention may be embodied to especial advantage in tubes for the generation of X-rays, which are superior to prior X-ray tubes in that the total X-radiation produced is available for use, so that the new tubes are peculiarly adapted for applications in which a large area of a specimen is to be irradiated, as, for example, for therapeutic purposes, for the production of photochemical changes, etc. As X-ray tubes constructed in accordance with the invention make use of all the features thereof, examples of such tubes will be illustrated and described in detail for purposes of explanation.

Up to the present, X-ray tubes have commonly been so constructed that only a small part of the total radiation generated can be used. The radiation issues from the target in all directions within the 180° solid angle or hemisphere subtended by the plane of the target face and at anode voltages of the order of 50 kv. or less, the intensity of the radiation is substantially uniform throughout that hemisphere. However, a large part of the radiation is eclipsed by the cathode and its supporting structure, which lie within the hemisphere of radiation, and, in addition, it has been the common practice to provide windows of relatively small area for the egress of the rays, so that the available radiation is still further reduced. For diagnostic and radiographic applications, in which information is provided as a result of modification of the X-ray beam caused by differential absorption by the objects through which it passes, the utilization of only a small part of the radiation is satisfactory, and that is true also with respect to industrial uses of X-rays for ascertaining the internal structure of specimens or for crystal analysis. For applications such as the production of photochemical reactions, etc., in which the beam produces changes in the object being irradiated, the impossibility of utilizing the total

radiation generated is an objectionable feature of present tubes.

An X-ray tube embodying the present invention is adapted to produce X-rays of high intensity, because of the large cathode employed, and the entire amount of radiation produced may be put to use, because the cathode and its supporting means are so constructed and arranged relative to the anode that they lie wholly outside the hemisphere of radiation leaving the target surface and, thus, do not have the eclipsing effect, as in prior X-ray tubes. In addition, the window of the new tube is of such size, shape, and location, with relation to the anode and cathode, that it deflects the electrons leaving the cathode and focuses them upon the anode face and it also permits the egress of all the X-rays generated.

For a better understanding of the invention, reference may be had to the accompanying drawings, in which:

Fig. 1 is a view in longitudinal section of one form of X-ray tube embodying the invention;

Fig. 2 is a sectional view on line 2—2 of Fig. 1;

Fig. 3 is a sectional view on an enlarged scale on the line 3—3 of Fig. 2;

Fig. 4 is a longitudinal sectional view through an X-ray tube of modified construction, which is provided with means for the irradiation of materials;

Fig. 5 is a sectional view on the line 5—5 of Fig. 4;

Figs. 6, 7, 8, and 9 are sectional views through the anode end of the new X-ray tube, showing different constructions producing different paths of travel of the electrons from the filament to the target;

Figs. 6a, 7a, 8a, and 9a are views showing the focal spots produced by travel of the electrons along the paths illustrated in Figs. 6, 7, 8, and 9, respectively;

Fig. 10 is a longitudinal sectional view through an X-ray tube of modified construction;

Fig. 11 is an end view of the tube shown in Fig. 10; and

Fig. 12 is a fragmentary longitudinal sectional view of another form of the new X-ray tube.

The X-ray tube illustrated in Fig. 1 comprises an evacuated envelope comprising a re-entrant end section of glass, united by a metal sleeve 50 to a cylindrical metal section 22. The section 22 is formed at its open end with an internal circumferential channel in which is seated the rim or base of a window 23, which is of dished or dome formation. The window is preferably made of beryllium or the beryllium alloy

of Claussen Patent 2,036,592, issued December 29, 1942, and the rim of the window is brazed in the channel with a vacuum-tight seal. A tubular shield 24 is mounted at the inner end of the section 22 to project beyond and protect the metal-glass seal between the glass section 20 and the metal sleeve 21 against electron bombardment.

A cathode in the form of a metal ring 25 is mounted within the outer end of section 22 in a circumferential seat provided for the purpose. This ring is formed with a circumferential channel 26 facing outwardly and a filament 27, which may be helically wound on a plain wire, is mounted within the channel on a plurality of metallic stems 28 spaced angularly about ring 25 and extending through insulating bushings 29 seated in openings through the ring leading to the channel. The filament is, accordingly, substantially circular in shape and it lies in a plane. A conductor 30, adapted to be connected to a source of filament current and sealed through the wall of glass section 20, extends through one of the bushings 29 and supports and is connected to one end of the filament. The other end of the filament is connected to a stem 31, which is mounted in an opening through ring 25 leading to channel 26 and is in electrical contact through the ring with the metal envelope section 22 and window 23. The section 22 is grounded in any appropriate fashion and the cathode is likewise at ground potential.

A hollow metallic anode shank 32 is mounted within the envelope by attachment to a sleeve 33 sealed in the end of the re-entrant portion of glass section 20. The shank carries a target disc 34 on its inner end and the disc faces the interior of the window and is substantially concentric therewith. The outer or target surface of the disc is substantially plane and lies substantially parallel to the plane, in which the filament lies, and the target surface lies closer to the window than the plane of the filament. A metal tube 35 extends into the re-entrant end of the envelope section 20 and is seated in an internal channel in the end of the anode shank 32. At its outer end, the tube enters a metal fitting 36. A metal tube 37 of smaller diameter than tube 35 extends through the fitting 36 and tube 35 concentrically with the latter and into the anode shank to terminate close to the end wall thereof behind the target disc. A line 38, connected to a source of cooling fluid, delivers cooling fluid to tube 37 to be conducted thereby through the anode shank and discharged against the wall at the back of the target. The fluid then returns through the space between tubes 35 and 37 to be discharged through line 39. The anode may be connected to a source of high potential through a conductor 40 leading to fitting 36, and lines 38 and 39 contain sections of insulating tubing of substantial length to insulate the anode.

In the operation of the tube, the anode is maintained at a high positive potential while the cathode and the window are at ground potential. The inner wall 25a of the channel 26 in the cathode projects outwardly beyond the end of the outer wall of the channel in the direction of the axis of the cathode. Accordingly, the electrons leaving the filament are focused by the inner wall 25a so that they are projected into the hemisphere subtended by the plane of the target face and, initially, they travel in a direction parallel to the axis of the anode. As the electrons pass beyond the edge of wall 25a, they are deflected inwardly by the action of the window, as indicated at 41, so that they are focused and impinge upon the face of the target.

The relation of the window to the cathode and the face of the target determines the trajectories of the electrons, and, in turn, determines the shape of the focal spot. In the construction shown in Fig. 6, the window 23 lies so close to the target that the paths of the electrons are of relatively short radius, and the focal spot produced is of the shape illustrated at 42 in Fig. 6a. When the space between the target and window is substantially increased, as shown in Fig. 7, the electron paths are of greater radius, so that the electrons from one point on the filament may pass across the face of the target to strike the target surface beyond its center. Under those conditions, the focal spot is of the shape indicated at 43 in Fig. 7a. Both the focal spots 42, 43 have a recess because of the gap in the source of electrons represented by the space between the ends of the filament. By proper spacing of the window and target surface, as shown in Fig. 8, the electrons may be caused to impinge at the center of the target to produce a substantially circular focal spot 44, as shown in Fig. 8a, and a similar spot 45 (Fig. 9a) may be produced by slightly increasing the spacing between the window and the target surface, as shown in Fig. 9.

In the new tube, the cathode and the support therefor may lie wholly outside any hemisphere subtended by the plane of the target surface and the window is of such size and form that its base is outside that hemisphere. Accordingly, none of the radiation is intercepted and all of it may issue through the window.

The new X-ray tube is illustrated in Fig. 4 in a form suitable for the treatment of materials to produce changes therein, as, for example, the destruction of bacteria for the sterilization of food products, the production of photochemical changes, etc. For such purposes, the tube is provided with a circumferential flange 46 adjacent the window and a casing 47 is mounted on the flange to enclose the window. The casing has a circumferential flange 48, which may be secured to flange 46 by screws 49, a gasket 50 being interposed between the flanges to make a liquid-tight joint, before they are secured together. Casing 47 has a hollow stem 47a extending coaxially with the domed window and a tube 51 is mounted in the end of the stem and extends concentrically therewith to terminate close to the window. A concave plate 52 is mounted on the inner end of tube 51 to lie close to the window and the edge of the plate terminates close to the surface of flange 46, so that the plate, window, and flange define a thin chamber of substantial area. A spiral partition 53 may be mounted on the inner surface of plate 52 to extend close to the surface of the window and this partition may be provided with baffles 54 lying between its convolutions. The partition, together with plate 52 and the window, defines a spiral passage having an entrance end to which tube 51 leads, the discharge end of the passage lying at the rim of the plate 52.

In the use of the tube described, the material to be irradiated may be a gas or liquid or in the form of fine particles suspended in a gas or liquid. The fluid is supplied through a line 55 connected to the outer end of the stem 47a, and enters tube 51 to be conducted to the chamber between plate 52 and the window. The material flows over the surface of the window through a prolonged path to escape beneath the edge of plate 52. The material then flows back between the outer surface of the plate and the inner wall of the casing into the space within the stem 47a around

the outer surface of tube 54. The material escapes through a line 56 leading from the interior of stem 47a.

The degree of uniformity with which the material is irradiated depends on the thickness of the film of material flowing over the surface of the window in that the layers in the film near the window absorb some of the radiation and thus shield the material in layers remote from the window. For some purposes, it is not necessary to provide the spiral partition 53 and the baffles 54, but, in the event that the partition and baffles are not used, it is generally necessary to mount plate 52 close to the outer surface of the window so that the film of material between the plate and window is relatively thin. When the partition and baffles are employed, the film of material may be thicker, since it is not only exposed to the radiation for a longer period but also the material flows turbulently over the surface of the window and all parts of the material thus receive equal treatment.

The X-ray tube illustrated in Fig. 10 is provided with means by which the relative positions of the window and target surface may be varied to vary the focusing action of the window and, thus, produce focal spots of different forms. The tube includes a re-entrant glass section 20' connected by a metal sleeve 21' sealed in the end thereof, to a cylindrical metal section 22' which is grounded in any suitable way. An annular cathode 25' is seated within the outer end of section 22' and a helical filament 27' is mounted in a circumferential channel in the face of the cathode. One end of the filament is connected to a stem 30', which extends through an insulating bushing in an opening in the cathode and is connected to a conductor 57 leading through an opening in section 22'. A metallic sleeve 58 is sealed within the opening and the conductor extends through the sleeve and is sealed through the wall of a glass cup 59 sealed to the end of the sleeve. The conductor is connected outside the envelope to a source of filament current.

A domed window 23', which is preferably of beryllium or of the Claussen alloy, closes the end of section 23'. The window is provided with a lateral flange 60 secured against one face of a ring 61, which closely encircles the section 22' and is movable thereon. Another ring 62 encircles section 22' and is secured to a circumferential flange 63 projecting from the outer surface of the section. The rings are connected by angularly spaced screws 64 which extend through openings in ring 61 and are threaded into ring 62. A spring 65 encircles each screw and bears against the opposed faces of the rings at its ends. The springs tend to force ring 61 outwardly away from ring 62 and the screws 64 limit such outward movement. A plurality of screws 66 threaded through ring 61 bear against the outer face of ring 62 and serve as a means by which ring 61 may be moved toward and away from ring 62 within the limits permitted.

A metallic bellows 67 encircles section 22' of the envelope and its ends are secured, respectively, to opposed faces of ring 61 and flange 63. A metal tube 68 is mounted around the outer surface of the window adjacent flange 60 and a cooling fluid may be passed through the tube to help dissipate the filament energy.

The tube of Fig. 10 contains an anode 32' having a flat target disc 34' at its outer end, the anode being mounted on a sleeve 33' sealed in the re-entrant end portion of the envelope section

20'. Cooling fluid is introduced into the anode through a metal fitting 36' and a tube 37' leading therefrom into the anode to terminate close to the end wall thereof. The fluid returns through the space within the anode outside tube 37' and through a space between that tube and a metal tube 35' which encloses tube 37' and extends from the outer end of the anode to fitting 36'. The discharged fluid leaves the fitting through a line 10 33'. The anode is connected to a source of high potential through a conductor 40', which may be connected to fitting 36'.

The relation between the window and the target surface of the tube shown in Fig. 10 may be varied 15 by turning the screws 66 and thus moving ring 61 and the window toward or away from the stationary ring 62, while the bellows 67 contracts or expands. The bellows forms part of the tube envelope enclosing the evacuated space and, since 20 there is a possibility of leakage at the joints between the ends of the bellows and the parts to which they are connected, the glass section 20' is provided with a hollow neck 69, which may be connected to a pump operable during the use of 25 the tube to maintain the vacuum therein.

Instead of varying the focusing effect of the window by altering the relative positions of the window and target surface, the same results may be obtained by varying the potential maintained 30 on the window. For this purpose, the construction illustrated in Fig. 12 may be employed. The tube shown in Fig. 12 includes an envelope having a metallic section 22a, within which is the cathode 25a and the anode 32a provided with a 35 target disc 34a. The tube includes a beryllium window 23a of dome shape, the rim of which enters and is brazed to a ring 70 of Monel metal. Ring 70 is soldered to the outer surface of a cup 71 made of the alloy known commercially as 40 "Kovar." The rim of cup 71 is sealed in one end of a glass ring 72 and the rim of a second "Kovar" cup 73 is sealed in the other end of the glass ring. At its other end, the cup 73 lies against and is soldered to the face of a shoulder 74 formed in 45 the tube section 22a. The glass ring insulates the window from the cathode and tube section 22a and the window is connected through a rheostat 75 to the negative side of a battery 76, the positive side of which is grounded. With this arrangement, the window may be maintained at a variable negative potential relative to the cathode 50 so as to have a variable focusing effect upon the electrons leaving the cathode and traveling to the surface of the target.

55 In the several X-ray tube constructions illustrated, the envelope is formed partly of metal and partly of glass, and the window is described as being made of beryllium or of the Claussen alloy, these metals being chosen because of their 60 low X-ray absorptive power. For some purposes, however, it is satisfactory to form the tube with a glass envelope, of which a domed portion of a thickness of the order of 1 m. m. forms the window. Such a window will collect a charge, which 65 will assist in focusing the electrons, although provision should be made in the usual way to prevent the accumulation upon the window of so great a charge that puncture may result. Also, in tubes to be operated at voltages of 150 kv. and 70 higher, the window may be made of any suitable metal, such as copper, aluminum, or stainless steel, the latter being desirable because of its resistance to corrosion. In discharge tubes other than for X-ray purposes, the focusing means will 75 lie within the hemisphere subtended by the plane

of the target surface and may be mounted wholly within the envelope or may form part of the envelope, as desired. In such devices, the X-ray absorption characteristics of the metal used for the focusing means is unimportant and, therefore, beryllium or the Claussen alloy need not be employed.

In the tube shown in Figs. 1 and 10, the cathode and its supporting means lie wholly to the rear of a plane through the target surface, so that they are entirely outside the hemisphere of radiation. In the tube shown in Fig. 4, the extreme end of the cathode projects into the hemisphere of radiation to a small extent, but substantially all of the radiation is available. In all devices embodying the invention, the cathode is unusually large so that a large quantity of electrons is produced and X-ray tubes embodying the invention are, accordingly, adapted for the production of high intensity X-radiation. Also, in such X-ray tubes, the area of the window is such as to permit substantially all the radiation to pass therethrough.

I claim:

1. An X-ray tube which comprises an evacuated envelope, an anode including a substantially plane target surface within the envelope, and a cathode including a filament within the envelope and in such relation to the anode that electrons from the filament travel to the face of the target, the cathode lying substantially entirely outside any hemisphere subtended by the plane of the target surface and the envelope including a window relatively more permeable to X-rays than the remainder of the envelope and of such shape and location relative to the target surface that substantially all the radiation emanating from the target face passes through the window.

2. An X-ray tube which comprises an evacuated envelope, anode and cathode means within the envelope, the cathode means including a filament, the filament lying coaxially of the anode and in such relation thereto that electrons travel along curved paths from the filament to the anode, and a metallic window for egress of the X-rays forming part of the envelope wall, the window being electrically connected to the cathode means to be maintained at substantially the potential thereof and acting on the electrons issuing from the filament to assist in causing them to travel along said curved paths to the anode.

3. An X-ray tube which comprises an evacuated envelope, an anode including a substantially plane target surface within the envelope, a cathode including a filament within the envelope, the filament having substantially the form of a circle about the center of the target surface and of larger diameter than the target surface and the cathode being in such relation to the anode that all the electrons from the filament that travel to the anode move along curved paths, a window forming part of the envelope and of larger diameter than the filament for egress of the rays.

4. An X-ray tube which comprises an evacuated envelope, an anode including a substantially plane target surface within the envelope, and a cathode including a filament within the envelope, the filament being of substantially closed form with its ends close to one another and substantially concentric with the target surface, the filament defining an area of greater transverse dimensions than the target surface and the cathode being in such relation to the target surface

5 that all the electrons that travel from the filament to the anode, move along curved paths.

5 6. An X-ray tube which comprises an evacuated envelope, an anode including a substantially plane target surface within the envelope, and a cathode including a filament within the envelope, the filament lying spaced laterally from the projecting area of the target surface and substantially entirely outside any hemisphere subtended by the plane of the target surface.

10 7. An X-ray tube which comprises an evacuated envelope, an anode including a substantially plane target surface within the envelope, a cathode including a filament within the envelope, the cathode lying substantially entirely outside any hemisphere subtended by the plane of the target surface, and a window for egress of X-rays forming part of the wall of the envelope, the window lying within said hemisphere.

15 8. An X-ray tube which comprises an evacuated envelope, an anode including a substantially plane target surface within the envelope, a cathode including a filament within the envelope, the cathode lying substantially entirely outside any hemisphere subtended by the plane of the target surface, and a window for egress of X-rays forming part of the wall of the envelope, the window being of dished shape and having the major portion of its area within said hemisphere.

20 9. An X-ray tube which comprises an evacuated envelope having a window for egress of the rays, an anode within the envelope having a substantially plane target surface facing the window and substantially concentric therewith, and a cathode within the envelope having a filament lying substantially in a plane parallel to the plane of the target surface and substantially outside any hemisphere subtended by the plane of the target surface, the filament lying wholly outside the projected area of the target surface.

25 10. An X-ray tube which comprises an evacuated envelope having a metallic window for egress of the rays, the window being of dished shape, an anode within the envelope having a substantially plane target surface, the rim of the window lying adjacent the plane of the target surface, and a cathode including a filament within the envelope, the filament lying substantially entirely outside any hemisphere subtended by the plane of the target surface and being electrically connected to the window.

30 11. An X-ray tube which comprises an evacuated envelope having a metallic window for egress of the rays, an anode having a target surface within the envelope, and a cathode having a filament within the envelope, the filament being substantially concentric with the target surface and defining an area greater than that of the target surface, the window being connected electrically to the filament and being adapted to act as a focusing means for the electron beam leaving the filament.

35 12. An X-ray tube, the combination of an anode having a substantially plane target surface and a cathode including a filament lying substantially in a plane parallel to the plane of the target surface and defining an area greater than that of the target surface.

40 13. An X-ray tube which comprises an evacuated envelope having a metallic window for egress of the rays, an anode having a target surface within the envelope, and a cathode having a filament within the envelope, the filament being substantially concentric with the target surface and defining an area greater than that of the target surface.

45 14. An X-ray tube which comprises an evacuated envelope having a metallic window for egress of the rays, an anode having a target surface within the envelope, and a cathode having a filament within the envelope, the filament being substantially concentric with the target surface and defining an area greater than that of the target surface.

50 15. An X-ray tube which comprises an evacuated envelope having a metallic window for egress of the rays, an anode having a target surface within the envelope, and a cathode having a filament within the envelope, the filament being substantially concentric with the target surface and defining an area greater than that of the target surface.

55 16. An X-ray tube which comprises an evacuated envelope having a metallic window for egress of the rays, an anode having a target surface within the envelope, and a cathode having a filament within the envelope, the filament being substantially concentric with the target surface and defining an area greater than that of the target surface.

60 17. An X-ray tube which comprises an evacuated envelope having a metallic window for egress of the rays, an anode having a target surface within the envelope, and a cathode having a filament within the envelope, the filament being substantially concentric with the target surface and defining an area greater than that of the target surface.

65 18. An X-ray tube which comprises an evacuated envelope having a metallic window for egress of the rays, an anode having a target surface within the envelope, and a cathode having a filament within the envelope, the filament being substantially concentric with the target surface and defining an area greater than that of the target surface.

70 19. An X-ray tube which comprises an evacuated envelope having a metallic window for egress of the rays, an anode having a target surface within the envelope, and a cathode having a filament within the envelope, the filament being substantially concentric with the target surface and defining an area greater than that of the target surface.

75 20. An X-ray tube which comprises an evacuated envelope having a metallic window for egress of the rays, an anode having a target surface within the envelope, and a cathode having a filament within the envelope, the filament being substantially concentric with the target surface and defining an area greater than that of the target surface.

ated envelope having a metallic window for egress of the rays, an anode having a target surface within the envelope, a cathode having a filament within the envelope, the window being connected electrically to the filament and adapted to focus the electrons passing from the filament to the target surface, and means for varying the relative positions of the target surface and the window to vary the focusing action of the latter and produce a selected focal spot.

14. An X-ray tube which comprises an evacuated envelope having a metallic window for egress of the rays, an anode having a target surface within the envelope, a cathode having a filament within the envelope, the window being connected electrically to the filament and adapted to focus the electrons passing from the filament to the target surface, and means for varying the position of the window relative to the target surface to vary the focusing action of the window and produce a selected focal spot.

15. An X-ray tube which comprises an evacuated envelope having a metallic window of outwardly dished form at one end, an anode within the envelope having a target surface facing the concave surface of the window, a cathode within the envelope having a filament lying substantially concentric with the anode and spaced laterally from the target, the window and filament being electrically connected, whereby the window is adapted to focus electrons to cause them to travel along a curved path from the filament to the target surface, and means for altering the relative positions of the window and target surface to vary the focusing action of the window.

16. An X-ray tube which comprises an evacuated envelope, an anode within the envelope having a target surface, a cathode within the envelope having a filament spaced laterally from the target surface, and focusing means adjacent the filament for directing electrons from the filament in the same general direction as the axis of the anode and away from the target surface, the envelope having a wall acting as an additional focusing means for the electrons between the filament and the target surface.

17. An X-ray tube which comprises an evacuated envelope, an anode within the envelope having a substantially plane target surface, a cathode within the envelope having a filament, and a focusing element having a channel surrounding the target surface and offset laterally therefrom, the channel facing in the same direction as the target surface and the filament being mounted within the channel, the envelope having a wall lying close to the curved path of the electrons between the filament and target surface and assisting in directing the electrons along that path.

18. An electron discharge tube which comprises an anode having a substantially flat face, a cathode including a filament surrounding the anode and lying in a plane parallel to the face of the anode and substantially entirely outside any hemisphere subtended by the plane of the anode face, means forming part of the cathode for directing electrons from the filament into such a hemisphere, and means within said hemisphere for deflecting the electrons and focusing them onto the anode face.

19. An electron discharge tube which comprises an anode having a substantially flat face, means lying substantially entirely outside any hemisphere subtended by plane of said face for emitting a hollow beam of electrons traveling into the

hemisphere, and means within such a hemisphere for deflecting the electrons to cause them to form a beam of smaller cross-section striking the anode face.

5 20. An electron discharge tube which comprises an evacuated envelope, an anode within the envelope having a substantially flat face, means within the envelope lying substantially entirely outside any hemisphere subtended by the plane of said face for emitting a hollow beam of electrons traveling into the hemisphere, means within such a hemisphere adapted to be maintained at a potential such that said means deflect the electrons and cause them to strike the anode face, and means for varying the potential on said deflecting means.

10 21. An electron discharge tube which comprises an evacuated envelope, an anode within the envelope having a substantially flat face, means within the envelope lying substantially entirely outside any hemisphere subtended by the plane of said face for emitting a hollow beam of electrons traveling into the hemisphere, and means forming part of the wall of the envelope for deflecting the electrons and causing them to strike the anode face.

15 22. An X-ray tube which comprises an evacuated envelope, an anode within the envelope having a substantially flat face, a cathode inside the envelope encircling the anode, the cathode lying substantially entirely outside any hemisphere subtended by the plane of the anode face and being operable to project a hollow beam of electrons into that hemisphere, a metallic window forming part of the envelope for egress of the X-rays, the window being insulated from the cathode, and means for maintaining the window at a potential such that it is effective to deflect the electrons entering such a hemisphere and cause them to strike the anode face.

20 23. An electron discharge tube which comprises an anode having a substantially plane face, a cathode including a filament surrounding the anode and lying substantially in a plane parallel to the plane of the anode face and substantially entirely outside any hemisphere subtended by the plane of the anode face, and an envelope enclosing the anode and cathode, the envelope having a portion of domed shape adjacent the anode and cathode acting to focus electrons emitted by the filament upon the anode face.

25 24. An electron discharge tube, a cathode comprising an annular element having a channel in one of its faces which extends transverse to the axis of the element, the channel extending coaxially with the element and the inner wall of the channel terminating in a plane lying outward beyond a plane through the end of the outer wall of the channel, and a filament of generally circular form mounted within the channel.

30 25. An X-ray tube which comprises an evacuated envelope, an anode having a target surface within the envelope, and a cathode including a filament within the envelope, the filament encircling the axis of the anode extending through the target surface and lying in such relation to the anode that electrons from the filament travel to the target surface, the cathode lying substantially entirely outside the path of any radiation issuing from the target surface in the operation of the tube and the filament lying wholly outside the projected area of the target surface.

35 26. An X-ray tube which comprises an evacuated envelope, an anode having a target surface within the envelope, a cathode including a fil-

ament within the envelope, the filament encircling the axis of the anode through the target surface and the cathode lying substantially entirely outside the path of any radiation issuing from the target surface in the operation of the tube, and means for deflecting electrons emitted by the filament to cause them to strike the target surface, said means including a member lying in the path of said radiation and means for maintaining the member at a negative potential. 10

27. In an electron discharge tube, the combination of an anode, a cathode structure including a filament of generally circular form, and a pair of focusing means for causing electrons emitted by the filament to converge along curved 15 trajectories toward a central axis normal to the plane of the filament and to form a beam of substantially circular cross-sectional outline directed toward the anode, said beam having a diameter substantially less than that of the filament, one of said focusing means comprising a member having an annular focusing channel coaxial with the anode, in which the filament is mounted, and the other of said focusing means including a concave member lying coaxial with said first member and with its concave surface adjacent the path

of electrons leaving the filament and effective to deflect them towards the anode.

CAPERTON B. HORSLEY.
